COMBINED BOWL AND COLANDER

Peter Schlumbohm, 41 Murray St., New York, N.Y.

Filed Nov. 30, 1960, Ser. No. 63,032

Term of patent 14 years

(Cl. D44—15)

Fig. 2

Fig. 3

FIG. 1 is an elevational view of a combined bowl and colander, showing my new design;

FIG. 2 is a top view thereof; and

FIG. 3 is an exploded elevational view thereof.

I claim:

The ornamental design for a combined bowl and colander, as shown.
